(57) **CLAIM**

The ornamental design for a vehicle trunk panel, as shown and described.

DESCRIPTION

FIG. 1 is a front right side perspective view of a vehicle trunk panel, showing our new design;

FIG. 2 is a front left side perspective view thereof;

FIG. 3 is a front bottom perspective view thereof;

FIG. 4 is a front bottom perspective view thereof;

FIG. 5 is a rear top perspective view thereof;

FIG. 6 is a rear top perspective view thereof;

FIG. 7 is a front bottom perspective view thereof;

FIG. 8 is a rear bottom perspective view thereof;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the drawings illustrate portions of the vehicle trunk panel that form no part of the claimed design.
